DESIGN FOR A CENTER BRIDGE FOR EYE- GLASSES OR SIMILAR ARTICLES

Raymond L. Obrig, East Orange, N. J., assignor
to Continental Optical Company, Inc., Roches-
ter, N. Y., a corporation of Indiana

Application June 22, 1936, Serial No. 63,436

Term of patent 3½ years

To all whom it may concern:

Be it known that I, Raymond L. Obrig, a citizen of the United States of America, residing at East Orange, in the county of Essex and State of New Jersey, have invented a new, original, and ornamental Design for a Center Bridge for Eye-glasses or Similar Articles, of which the following is a specification, reference being had to the accompanying drawing forming a part thereof.

In the drawing:

Fig. 1 is a front elevation of a center bridge for eyeglasses or similar articles showing my new design;

Fig. 2 is a rear elevation of the same;

Fig. 3 is a top plan view;

Fig. 4 is a bottom plan view;

Fig. 5 is a sectional view on line 5—5 of Fig. 2;

Fig. 6 is a front perspective view, and

Fig. 7 is a partial end perspective view taken from the rear.

Applicant's design includes a bridge having a horizontal portion at the top connecting with arms that extend downwardly in a vertical direction and terminate in U-shaped connecting portions which extend first rearwardly and then forwardly, and pad arms which are connected to and supported at the inner surfaces of said rearwardly extending portions, the pad arms extending thence rearwardly and downwardly and having their lower extremities attached to the nose pads.

I claim:

The ornamental design for a center bridge for eyeglasses or similar articles as shown and described.

RAYMOND L. OBRIG.
